UNITED STATES PATENT OFFICE.

GEORGE TREVIRANUS, OF DULUTH, MINNESOTA.

CAR SWEEPER OR SCRAPER.

No. 853,385.

Specification of Letters Patent.

Patented May 14, 1907.

Application filed December 9, 1904. Serial No. 236,184.

To all whom it may concern:

Be it known that I, GEORGE TREVIRANUS, a citizen of the United States, residing at Duluth, in the county of St. Louis and State 5 of Minnesota, have invented certain new and useful Improvements in Car Sweepers or Scrapers; and I do hereby declare the following to be a full, clear, and exact description of the invention, such as will enable others skilled in the art to which it appertains to make and use the same.

My invention relates to car sweepers, and has for its object the provision of means for sweeping or scraping earth, iron ore, or other 15 minerals from cars.

With this and other objects in view, it consists of a frame or rolling bridge adapted to move along and upon a suitable track and to span the track, or tracks, or roadway of the 20 vehicles from which the material is to be swept, a carriage mounted on said frame and adapted to move longitudinally thereof and transversely of the second said tracks or 25 transversely of said roadway, a vertically adjustable set of sweeping or scraping blades mounted on said carriage, means for moving said frame or bridge upon its supporting tracks, means for moving said carriage longitudinally of said bridge, and means for vertically adjusting said set of sweeping or 30 scraping blades.

It also consists of certain other constructions, combinations and arrangements of parts as will be hereinafter described and 35 claimed.

In the drawings, Figure 1 is a side elevation of said invention. Fig. 2 is a top plan view of the same and Fig. 3 is a front elevation of the same, showing in vertical transverse section a car from which the mineral 40 has been scraped by the blades forming part of said invention.

In the drawings, 1 is a frame or bridge, mounted on wheels 2, which wheels are 45 adapted to roll on tracks comprising the sills 3 and 3^a, chairs 4 and 4^a and rails 5 and 5^a. In order to prevent said frame from lifting from the rails 5 and 5^a, fingers 1^a are formed on said frame and adapted to extend under 50 the wheel-contacting flanges of the respective said rails. It is obvious however that said frame and said rails or roadway may be modified or altered in many ways without departing from the spirit of my invention, 55 and I do not therefore desire to be restricted to the exact construction to those parts as

shown. Forming part of said frame are ways 1^b, upon which is mounted and adapted to slide a carriage 6. In order to move said carriage on said frame, I provide a horizontal rack 7 secured to said frame, and upon said carriage I mount in suitable bearings secured thereto a vertical shaft 8 upon which, at or near its lower end, is rigidly mounted a pinion 9 adapted to engage said rack. Upon the upper end of said shaft is a crank handle 65 for turning said shaft. Mounted in suitable guides 10 forming part of said carriage is a vertically movable frame 11 of any suitable construction, to the lower end of which is secured a set of sweeping or scraping blades 11^a, preferably of such different lengths and end-contours that the front elevation of the set will conform approximately to the cross section of an ore car or of such car as it may 70 be used for sweeping. In order to raise and lower said frame 11, there are secured thereto oppositely directed vertical racks 12 and 13, and in suitable bearings mounted on said carriage are journaled shafts 14 and 15, upon which, respectively, are rigidly secured two pinions 14^a and 15^a adapted to engage the 75 relatively corresponding said racks 12 and 13. Upon said shafts 14 and 15 are also rigidly secured the belt wheels 14^b and 15^b, preferably of the sprocket wheel type, which are belted by belts 14^c and 15^c, respectively, to belt wheels 16 and 17, respectively, which latter wheels are both journaled on a suitable 80 sleeve which is mounted upon shaft 19, 85 which, in turn, is journaled in suitable bearings mounted on said frame. Said sleeve is carried by a bracket 18 extending from said carriage 6. Thus when said carriage moves along said frame it will through the medium of said bracket push said sleeve along 90 said shaft 19. The wheels 16 and 17 will thus be kept in alinement with the wheels 14^b and 15^b respectively. But since the last 95 named result may be accomplished in other ways within the scope of my invention, I do not desire to limit myself to the exact construction shown. Slidably keyed upon said shaft 19, are clutches 16^a and 17^a of any suitable construction, adapted to engage the 100 respectively contiguous wheels 16 and 17, the clutches being preferably connected by straps 16^b and the construction being such that when the clutch 16^a is moved toward the wheel 16 the clutch 17^a will consequently be 105 moved away from the wheel 17 and vice versa. In order to operate said clutches, I

provide a lever 20, pivoted at its lower end as at 20^a to the carriage 6, and pivoted intermediate of its ends to said clutch 16. If desired a toothed segment not shown may be attached at a convenient place to said carriage to engage the upper end of said lever and hold said lever at the desired angle for engaging either of said clutches with its corresponding wheel or for holding said clutches out of engagement with either of said wheels. It will be observed that while said pinions 14^a and 15^a will rotate in the same direction, their operation upon said frame 11 will be different because of their engagement with the oppositely directed racks. Thus the pinion 14^a will operate to raise said frame 11 and the pinion 15^a will operate to lower said frame 11. In order to rotate said shaft 19, I preferably mount upon said frame 1 an electric motor 21, connected in any suitable manner to any suitable source of electricity, suitable switches being placed in the conductor between said source and said motor and located on said carriage 6 within reach of an operator standing on a suitable platform 22 erected upon said frame 1. Said motor and connections may be any such suitable ones as are well known to the art of electric motors and means for operating them, and it is therefore believed unnecessary to further describe them herein. Upon the armature shaft of said motor is keyed a belt wheel 23 connected by a belt 23^a with a belt wheel 24 which is keyed to said shaft 19. A belt wheel 25 is also keyed to said armature shaft and is connected by a belt 25^a with a belt wheel 26 keyed to a suitable shaft journaled in suitable bearings on said frame 1; a gear wheel 27 is also keyed to the last said shaft and is adapted to mesh with a gear wheel 28 keyed to a suitable shaft journaled in suitable bearings on said frame 1. Upon the same shaft with the gear wheel 26 is keyed a second belt wheel 29 which is coupled by a belt 29^a to a belt wheel 30 journaled on a shaft 31 which is journaled in suitable bearings 32 on said frame 1. Upon the same shaft with the gear wheel 28 is keyed a belt wheel 33 which is coupled by a belt 33^a to a belt wheel 34 journaled upon said shaft 31. It will now be observed that said wheel 30 will revolve in one direction on said shaft 31 and that said wheel 34 will rotate in the opposite direction on said shaft. In order to rotate said last named shaft with either of said wheels 30 or 34, I provide the clutches 30^a and 34^a slidably keyed to said shaft and connected together by suitable straps 30^b. To said clutch 30^a I pivotally secure a draw rod 35, to the opposite end of which I pivotally secure one end of a lever 36, which lever is pivoted intermediate of its ends to the frame 1, as at 36^a. It will now be observed that by swinging said lever in one direction the clutch 30^a will be thrust into engagement

with the side face of the wheel 30 and power communicated from said wheel through said clutch to the shaft 31, while by swinging the lever 36 in the opposite direction the clutch 30^a will be disengaged from the wheel 30 and the clutch 34^a will be carried into engagement with the wheel 34 and power communicated from the latter wheel to reverse the rotation of said shaft. Upon the opposite ends of said shaft 31 are keyed belt wheels 37 which are coupled by belts 38 to belt wheels 39 which are keyed to the shafts of the supporting wheels 2 of said frame 1. Thus the rotation of the shaft 31 will cause the supporting wheels 2 to move said frame along said track in one direction or the other as the case may be.

In operation, my said invention will usually be erected on a dock equipped with ore pockets, which pockets will be so located as to be adapted to receive the ore scraped from the vehicles to be unloaded. Said vehicles will usually be of the type of ore cars which are provided with trap doors in their floors and have inclined slides. Such a car, alone or forming part of a train, being positioned over a pocket and beneath said bridge, the trap doors are opened and a large part of the ore is released therethrough by gravity. The carriage on said bridge is then brought over the end of the car and the scraping blades are lowered into the ends of the car. The bridge is then moved along its supporting tracks far enough to cause said blades to scrape the remaining ore to the trap door openings. The operation may be repeated from either end of the car as often as necessary. The train may then be drawn forward to remove the empty car and bring a full car over the pocket, or, after such pocket is filled said bridge may be moved on its supporting tracks to a position over another pocket. The bridge may span any suitable number of car tracks and the carriage on the bridge may be moved back or forth to a position over any desired one of said tracks.

Having now described my invention, what I claim and desire to secure by Letters Patent is,

In a car sweeper or scraper, the combination of a bridge adapted to span a railway track and to move in a parallel direction thereto, a carriage mounted on said bridge above said track and adapted to move transversely of said track, a vertically movable frame mounted on guides on said carriage and provided with oppositely directed vertical racks, pinions engaging said racks, a drive shaft journaled in bearings on said bridge, a motor, belt and belt wheel connections between said motor and said drive shaft, a sleeve carried by a bracket on said carriage and loosely engaging said drive shaft, belt wheels mounted on said sleeve and belted to respectively corresponding belt wheels.

mounted on the shafts of the respectively corresponding said pinions, clutches slidably keyed to said drive shaft at opposite sides of the belt wheels on said sleeve, means for operating said clutches alternately, a set of scraping or sweeping blades carried by and depending from said vertically movable frame, a second drive shaft journaled in bearings on said bridge, power transmitting means connecting said motor and said second drive shaft, means including said motor and said

second drive shaft for moving said bridge parallel with said track, and means for moving said carriage transversely of said track, substantially as described.

15

In testimony whereof I hereunto affix my signature, in presence of two witnesses.

GEORGE TREVIRANUS.
